UNITED STATES PATENT OFFICE.

FREDERICK H. HICKE, OF LA CROSSE, WISCONSIN.

GAGE FOR LIQUID-CONTAINING TANKS.

1,269,709.

Specification of Letters Patent. Patented June 18, 1918.

Application filed December 6, 1917. Serial No. 205,804.

To all whom it may concern:

Be it known that I, FREDERICK H. HICKE, a citizen of the United States, and a resident of La Crosse, in the county of La Crosse and State of Wisconsin, have invented a new and useful Improvement in Gages for Liquid-Containing Tanks, of which the following is a full, clear, and exact description, reference being had to the accompanying drawings, which form a part of this specification.

My invention relates to liquid containing tanks and has particular reference to a gage for the gasolene tank of an automobile, showing upon the dial the amount of gasolene in the tank.

The object of my invention is the provision of a new and simple device to manipulate the spindle to which is attached the pointer, thereby securing a gage of the utmost simplicity, strength, and durability.

I attain this object by means of the mechanism illustrated in the accompanying drawing, which forms a part of this specification in which—

Figure 1, is a view of the tank showing my improved gage attached. Fig. 2, a front view showing the position of the mechanism when the tank is empty; Fig. 3, a front view showing the position of the mechanism when the tank is full, with the position of the pointer shown on the dial; Fig. 4, a perspective view of the operating mechanism; Fig. 5, an enlarged front view of the operating pulley, showing the position of the slot; Fig. 6, an enlarged view of the cap to which is secured the bracket supporting the operating mechanism.

Similar numerals refer to similar parts throughout the several views.

Describing the parts 1 (Fig. 1) indicates the tank to which is securely fastened a cap 2 (Fig. 6) composed of an annular flange 3 the vertical member of which is threaded 45 to engage a retaining ring 4 also threaded to engage the annular flange 3.

A dial plate 5 preferably of metal suitably marked is placed on top of the upper edge of the annular flange 3; a packing ring 6 is placed upon the dial plate 5; placed on the packing ring 6 is a crystal 7 upon which is placed another packing ring 6. The retaining ring 4 when screwed on the annular flange 3 forms of the packing rings 6 and crystal 7 a gas-tight cap substantially as shown in Fig. 6.

At the lower side of the dial 5 and firmly secured thereto is a metal bracket 12 to conform to the design shown in Fig. 3. Passing through the bracket 12 and the dial 60 plate 5 is a spindle 8 one extremity forming a hook 18, the opposite extremity shouldered to receive the pointer 9 rigidly secured thereto.

To the spindle 8 collars 13 are secured to hold the spindle 8 at the necessary level.

Revolutely attached to the bracket 12 at 17, arranged to loosely engage the hook 18 of the spindle 8 is located the operating mechanism 14 comprising a flange 26 to 70 which is secured a peripherally grooved pulley 24—25 (Fig. 4), semi-circular in cross section and diagonally slotted as shown at 21—22—23 (Fig. 5).

Secured to the flange 26 is a rod 15 with a 75 float 16 attached.

The tank 1 having been filled with liquid, the float 16 rises to the position shown in Figs. 1 and 3; and the hook 18 loosely engaged in the slot 21, will turn to the position 80 shown at 19 at the extremity of the slot 21 marked 22, thereby turning the pointer 9 to the position shown on the dial 5 at 10, Fig. 3.

The liquid in the tank attaining a lower level, the float 16 will drop as shown by the 85 dotted line in Fig. 1, and when empty will be in the position shown at 27, thereby causing the operating device 14 to partly revolve.

The hook 18 loosely engaged in the slot 90 21 will follow the course of the slot, thereby causing the spindle 8 to revolve, and the float 16 attaining its lowest level, as shown at 27, the hook 18 of the spindle 8 will be on the opposite side of the operating pulley 24 at 23, pointing in the opposite direction as shown at 20 Fig. 2, thereby causing the pointer 9 to register across the face of the dial 5, to the position shown by the dotted pointer 11 Fig. 3.

By making the pulley 24 U-shaped in cross-section, I attain a saving of material and also throw the weight of the pulley to that side of the flange 26 opposite the float 16.

I do not consider that a device must be constructed exactly as illustrated and described herein, it being apparent that many variations in material, form, size, location and arrangement of the various parts can 110 be made without departing from the scope of my invention.

Having now described my invention, I desire to secure by Letters Patent:—

1. The combination, in a gage for liquid containing tanks, of a cap attached to the wall of the tank over an opening therein; a bracket attached to the cap; a flange revolvably attached to said bracket; firmly secured to the flange a peripherally grooved operating pulley having across the face thereof a groove or slot diagonally from side to side; a rod with float attached secured to the flange; a spindle having attached to its upper end a pointer; the lower end of the spindle forming a hook arranged to loosely slide along the course of the slot of the operating pulley.
2. The combination, in a gage for liquid containing tanks, of a cap attached to the wall of the tank over an opening therein, said cap having a dial and forming a gas-tight covering for said opening; a bracket attached to the underside of said cap; an operating device consisting of a flange revolvably attached to the lower end of said bracket; having firmly secured thereto a peripherally grooved pulley; across the face of said operating pulley and diagonal therewith, a slot; a rod with float attached, secured to said flange; a spindle revolvably

passing through the bracket and dial plate, 30 said spindle shouldered to receive the pointer on one end and formed at the opposite end into a hook to loosely engage the slot of the pulley.

3. The combination, in a gage for liquid containing tanks, of a gas tight cap attached to the wall of the tank over an opening therein; a dial in said cap having gradations marked thereon; a bracket firmly attached to the above mentioned cap; an operating device having a diagonal slot, a flange revolvably attached to the bracket, said device being secured to said flange; a spindle revolvably passing through the bracket and dial plate; a pointer attached 45 to the upper end of the spindle to extend across the face of the dial; a hook formed on the lower end of the spindle to loosely engage the operating device; and means to hold said spindle in place; all substantially 50 as set forth.

In testimony whereof, I attach my signature to this specification in the presence of two subscribing witnesses.

FREDERICK H. HICKE.
